CONTROL DEVICE FOR CABLE CONTROL
MECHANISMSGaston Bodinaux, Liège, and Armand Malchair,
Herstal, Belgium, assignors to Charles Somville,
Brussels, BelgiumApplication March 6, 1947, Serial No. 732,790
In Belgium February 28, 1946Section 1, Public Law 690, August 8, 1946
Patent expires February 28, 1966

8 Claims. (Cl. 74—489)

1

The control device, object of the invention, while ensuring a rectilinear action and an amplification effect, is essentially characterized from similar devices known, due to the extreme simplicity of its conception.

In fact, this device, shaped for instance as a control handle, comprises only a manipulating lever freely lodged in an appropriate casing, and held by the control cable, which is wound around the S-shaped profile head of said lever.

Although of a very simple and economical design, this control device has many advantages. The cable neither slips nor rubs on the moving parts and its free portions adjacent to the head of the lever are always displaced along a horizontal line and are not subjected to those flexion effects which cause rapid deterioration and rupture of the cable.

On the other hand, the displacements of the cable are large relatively to the slight displacements of the handle. Consequently, when for instance, the device is used as a brake control for a bicycle, a long brake stroke is obtained, that is to say:

(1) a big regulation possibility, as the distance separating the brake shoes from the felly of the wheel may be increased, resulting in the suppression of the warping action of said shoes on the wheel;

(2) a positive braking action, whatever may be the wear of the shoes;

(3) a possibility of using thicker shoes;

(4) a rapid and particularly supple braking, in spite of the bigger play existing between the shoes and the felly.

Moreover, the proposed construction reduces the pulling strain on the cable fixation means to the casing. Finally, it much facilitates dismounting of the wheel, specially in case of puncture.

As the manipulating lever constitutes really a floating piece in the casing in which it is mounted, this casing may be of very simple shape.

The appended drawing shows, as a non limitative example, a preferred embodiment of the new control device. In this drawing:

Figure 1 is an elevation showing the control handle in its casing;

Figures 2 and 3 are cross-sections through the casing before and after assembling respectively, and

Figure 4 is a side elevation of the casing.

In casing 1 is lodged head 3 of a lever 2 which is of steel, aluminum or any other metal or alloy, and is obtained by casting, punching or stamp-

2

ing. This lever is "floating" which means that it is simply kept freely in the casing 1 by a control cable 4, due to the special shape given to the head 3. The latter is provided in fact in its middle part with a groove A. B. C. having the shape of an S, which is extended at the right top part by a gradient A. D. and at its left lower part by a gradient C. E.

The end of cable 4 coming from the device 10 under control such as a brake or the like, is passed through a hole 5 bored into the front side face of the casing 1; it is then wound around the S profile of head 3, then leaves it to be secured in 15 to the small back side face of casing 1. The two free portions of the inlet and outlet cable 4 adjacent to head 3 are horizontal and tangent to the corresponding curves of head 3.

When released, the lever 2, maintained inside 20 casing 1 by the two stressed horizontal portions of cable 4, takes its inferior limit position and contacts the lower edge of the slot of the casing through which passes the handle of the lever.

A lug or nose 7, formed on the lower face of 25 the lever 2, engages said edge and prevents displacement of the lever to the left.

Upon actuation of the lever 2, the latter makes a rotation movement around a fictive axis. Gradient A. D. then comes gradually in contact with the top fixed horizontal portion of the cable, while simultaneously gradient C. E., moves rightwards and contacts the lower horizontal cable portion; thus cable 4 is longitudinally displaced towards the right along a horizontal line.

It is to be noted that cable 4 in its section A. B. 30 C. does not slip relative to the head 3, and that section A6 of the cable does not vary in length, only the portion C5 is lengthened.

Due to this particularity, the lengthenings of 35 portion C5 of the cable are amplified; to slight arcuate movements of lever 2, correspond relatively large lengthenings of section C5. Whatever could be the importance of the angle described by lever 2, the displacement of the cable is made along a horizontal line.

When the device is used as a bicycle brake 40 control, a substantial displacement of the cable is obtained long before handle 2 has reached its top limit position.

As soon as lever 2 is released, the pull exerted 45 on section C6 by the controlled device, displaces the portion CE of head 3 to the left, thereby returning the handle to its inferior limit position.

Of course, to lodge handle 2 as has just been described, a casing of any known construction 50 could be used. But it is preferred to use a cas-

ing of simple construction, having no protruding part and needing neither screws nor fixation bolts, such as represented on Figures 2 to 4.

In a casing of that type, the envelope or casing 1 proper, made of steel, aluminum or any other metal or alloy and the extremities of a collar 8, surrounding any supporting element such as the pipe 10 of a handle-bar, are maintained in abutting relation by means of two spring blades 9 welded or riveted respectively to the extremities of collar 8. Exterior lugs 11, formed at the base of blades 9, hook in appropriate slots 12 bored near the bottom of casing 1, whilst top lugs 13 of these blades 9 contact and press against pipe 10 of the handle-bar (Figure 3).

We claim:

1. In a control device for causing longitudinal displacement of a cable, a manipulating lever, a support frame, said lever comprising a head freely lodged in said frame and a handle projecting therefrom, said lever head having a substantially S-shaped, cable-receiving groove therein, and the cable to be displaced being arranged around the lever head in said groove and anchored at one end to said frame, whereby the head of the lever is bound and restrained in the frame by said cable and the free length of the latter is longitudinally displaced by lever manipulation.

2. In a control device as claimed in claim 1, the cable arranged so that the anchored end portion thereof extends tangentially from said S-shaped groove, and the free length thereof extends tangentially from the opposed end of said groove parallel to said anchored end portion.

3. In a control device as claimed in claim 1, said support frame constructed and arranged to confine the motion of the lever to a pivoting of the S-shaped head, and to limit the extent of said pivoting motion.

4. The combination with a control device comprising a support frame and a lever having a head freely lodged in said frame, said lever head being provided with a substantially S-shaped groove, of a cable anchored at one end to said frame, arranged around said groove and passing

freely away from said device; whereby said cable binds and restrains said lever head in the frame, and manipulation of the lever causes longitudinal displacement of the free length of cable in order to perform useful work.

5. The combination as claimed in claim 4, wherein the cable is arranged so that the anchored end-portion and the free length thereof extend, parallel and in mutually opposed sense, tangentially from said S-shaped groove.

6. The combination as claimed in claim 4, wherein a handle on said lever projects from said frame and the latter is shaped so as to confine the motion of the lever to a pivoting of the head thereof and to limit said motion.

7. In a control device for the brake cables of a vehicle having a steering gear, a support frame affixable to said steering gear and a manipulating lever projecting from said frame, said lever having a substantially S-shaped head freely lodged in said frame and the control end of the cable in question being wound around said S-shaped head and anchored to the frame, whereby manipulation of the lever causes pivoting of said head and hence longitudinal displacement of the cable.

8. In a control device as claimed in claim 7, said S-shaped head having extended portions prolonging the curved extremities of the S and adapted to positively contact and guide the cable as the latter is wrapped further around the head of the lever upon manipulation of the latter.
